BENJAMIN B. BETTS,
By His son & Daughter
1873.

UNITED STATES PATENT OFFICE.

BENJAMIN B. BETTS, OF ST. LOUIS, MISSOURI.

TIE-PLATE.

1,155,990.

Specification of Letters Patent.

Patented Oct. 5, 1915.

Application filed November 10, 1913, Serial No. 800,214. Renewed August 2, 1915. Serial No. 43,343.

To all whom it may concern:

Be it known that I, BENJAMIN B. BETTS, a citizen of the United States of America, and resident of St. Louis, Missouri, have invented certain new and useful Improvements in Tie-Plates, of which the following is a specification containing a full, clear, and exact description, reference being had to the accompanying drawings, forming a part 10 hereof.

My invention relates to improvements in tie plates, and the object of my invention is to construct a tie plate especially designed for use in connection with running rails and 15 guard rails wherein I have provided novel means for securing the rails to the plate and a novel means for preventing buckling of the plates.

With the above purposes in view my invention consists in certain novel features of 20 construction and arrangement of parts as will be hereinafter more fully described, pointed out in the claims and illustrated by the accompanying drawings, in which—

25 Figure 1 shows in plan a tie plate constructed according to my invention; Fig. 2 is a longitudinal sectional elevation of the plate taken on the line 2—2 of Fig. 3, and shows in place a running rail and a guard 30 rail; Fig. 3 is a transverse sectional elevation of the plate taken on the line 3—3 of Fig. 1; and Fig. 4 is an inverted plan of the plate on a reduced scale.

Referring by numerals to the accompanying drawings: 5 designates the body of the plate which has on its upper side extending substantially the width of the plate and adjacent one end thereof a rail-bearing surface 6 for the support of a running rail such as 7.

40 On the upper side of the body 5 to one side of and in a plane above the rail-bearing surface 6 is a rail-bearing surface 8 arranged for the support of a guard rail such as 9, the inner margin of the rail-bearing surface 8 45 overlapping the inner margin of the rail-bearing surface 6. By the placing of the one rail-bearing surface in a plane above the other and with its one margin overlapping the other rail-bearing surface unaltered 50 standard rails may be employed as a running rail and a guard rail.

Formed in the side of the body constituting the rail bearing surface 8 contiguous to the rail-bearing surface 6 is a rail-receiving 55 recess 10, and formed on said body above the recess 10 is a rib 11 in which there is a

recess 12 contiguous to the rail-bearing surface 8; each of the said recesses forming continuations of said rail-bearing surfaces. Formed in the rail-bearing surface 8 within 60 said recess 12 is a channel 13, the function of which will be hereinafter made clear.

Arising from the rail-bearing surface 8 next adjacent its margin opposed to the recess 12 is a rail-bearing shoulder 14. 65

Formed through the body of material having the rail-bearing surface 8 and intersecting the rail-bearing shoulder 14 are spike holes 15 and surrounding the sides and the back, but not the fronts of each of said holes, 70 is a spike backing 16.

Formed through the body 5 outside of the body having the rail-bearing surface 8 is a spike hole 17.

Arising from the body 5 removed laterally 75 from the rail-bearing surface 6 and in opposition to the recess 10 is a rail-bearing shoulder 18, and said shoulder 18 is spaced apart from said recess a distance greater than the width of the base of the rail. Formed 80 through the body 5 adjacent said shoulder 18 are the spike holes 19, the shoulder 18 extending over the backs and sides of said openings to act as spike backings.

20 designates a removable plate arranged 85 to normally rest against the shoulder 18 and be held in place by spikes which are driven through the openings 19.

21 designates a brace rising from the rib 11 and at an angle so that its uppermost 90 end will engage the underneath face of the ball of the running rail 7. The brace is so formed that its side margin will engage the web of the rail. By preference this web-engaging portion of the brace is a web 22, 95 the lowermost end of which forms a continuity of the recess 10.

Formed on the underneath face of the plate are a plurality of ribs 23 extending longitudinally of the plate. 24 designates 100 a rib extending transversely of the plate adjacent the spike holes 19. These ribs serve as anti-creeper to prevent movement of the plate relative to the tie.

By reason of the shoulder 18 being removed from the recess 10 a distance greater than the width of the running rail base, it is to be observed that the running rail may be seated in said recess by being moved laterally thereinto. In order to hold the 110 running rail fully seated in said recess and to provide a relatively long bearing for the

margin of the rail base opposed to the margin seated in said recess the plate 20 is employed which is placed between the rail base and the shoulder 18. Spikes are then driven 5 through the holes 19 and their heads, when fully seated, will overlie the rail base flange, the ends of the plate 20 and be backed by the portion of the shoulder 18 at the backs and sides of the spike holes.

10 By reason of the channel 13 lying within the recess 12 the guard rail may be removed from its rail-bearing surface even though the rail-bearing shoulder 14 is spaced apart from the recess 12 a distance equivalent to 15 the width of the base of the guard rail, the channel allowing tilting of the entire guard rail to a point where it will be above the shoulder 14.

The brace 21 is designed primarily to 20 prevent buckling of the body of the plate. Where guard rails are employed there is usually imparted to the guard rail lateral strains or thrusts when rolling stock passes thereover and this brace imparts such strains 25 or thrusts to the ball and web of the running rail, which has sufficient rigidity to resist such strains. If it were not for such a brace the side strain imparted to the ball of the guard rail would bear downwardly 30 on the end of the plate and exert an upward strain on the rib 11 thereby tending to buckle the plate. With all of the strain on the rib 11 resisted by the ball of the running rail through the medium of the 35 brace 21 this tendency toward buckling is obviated.

I claim:

1. A tie plate having a pair of rail-bearing surfaces one of which is arranged in a 40 plane above and overlapping the other, in-

tegral means forming a recess contiguous to each of said surfaces at their overlapped margins, shoulders arising from said surfaces in opposition to said recesses, one of said shoulders being spaced apart from its 45 companion recess a distance equal to the width of a rail base, the other shoulder being spaced apart from its companion recess a distance greater than the width of a rail base, there being a channel in said first 50 mentioned recess to provide for tilting the rail over said shoulder, and a removable plate arranged to be placed against the shoulder forming a companion to said second mentioned recess.

2. A combined running and guard rail tie-plate constructed as a unit and comprising a running-rail bearing surface, a guard-rail bearing surface arranged in a plane above and partially overlying the running 60 rail bearing surface, whereby the base flanges of rails supported on said surfaces will be overlapped, a rib having a recess therein to receive the base flange of the guard rail, a brace extending from said rib and terminating above and laterally removed from the rib to engage beneath the ball of a running rail, a rail bearing shoulder on each surface, and a channel in one 65 of said surfaces opposite the shoulder, and there being spike openings through each surface next adjacent said shoulders.

In testimony whereof, I have signed my name to this specification, in presence of two subscribing witnesses.

BENJAMIN B. BETTS.
